UNITED STATES PATENT OFFICE.

JOHN BISHOP, OF BARTOW, AND ANDREW PETER JERGUSON, OF HULL, FLORIDA.

DRIER.

SPECIFICATION forming part of Letters Patent No. 634,798, dated October 10, 1899.

Application filed February 27, 1899. Serial No. 706,994. (No model.)

To all whom it may concern:

Be it known that we, JOHN BISHOP, of Bartow, in the county of Polk, and ANDREW PETER JERGUSON, of Hull, in the county of De Soto, State of Florida, have invented a new and Improved Drier, of which the following is a full, clear, and exact description.

The purpose of this invention is to provide a rotary drum-drier of that class in which the material to be dried is caused to move longitudinally through the revolving drum and in which a drier of given dimensions will provide a greater heat-radiating surface than driers previously produced, thus increasing the efficiency of the drier, which efficiency of course depends upon the heat-radiating surface thereof.

This specification is the disclosure of one form of our invention, while the claims define the actual scope thereof.

Reference is to be had to the accompanying drawings, forming a part of this specification, in which similar characters of reference indicate corresponding parts in both the views.

Figure 1 is a longitudinal section of the drier, and Fig. 2 is an end view with parts broken away.

In driers of the type to which our invention relates the material to be dried in passing through the drum bears on the lower portion thereof and is little acted on by the upper portions of the drum. Consequently a minimum degree of effectiveness is attained.

Our invention consists in providing the drier with a number of longitudinal partitions, forming as many contracted longitudinal passages through the drier, through which passages the material to be dried is passed, thus providing a large amount of radiating surface, and consequently increasing the efficiency of the apparatus.

The cylinder or body portion *a* of the drier is provided with the partitions *b*, which in the present instance are four in number and are arranged radially with respect to the drum, being secured to the sides of the drum by angle-irons *c* and to each other by angle-irons *d*, thus forming four separate passages *e* in

the drum. The material being passed through these passages is subjected to a larger radiating-surface, and consequently more effectively treated.

The feed end *f* of the drier is provided with a number of diagonal angle-iron flanges *g*, which serve, as the drum revolves, to feed the material toward the partitions *b*. This material is thrown into the end *f* and taken up by the angle-irons as the drum revolves and led into the passages *e*. The partitions *b* are provided with angle-iron flanges *h*, which serve to advance the stock along the drum. These flanges *h* are useful only when the drum is mounted horizontally. When the drum is disposed at an incline, the flanges *h* will not be necessary.

Having thus described our invention, we claim as new and desire to secure by Letters Patent—

1. A drier-drum provided with a solid continuous diaphragm or partition extending longitudinally through the same to form the drum into a plurality of independent passages, said passages extending from the center of the drum to the sides thereof and through which the material to be dried is passed, thereby increasing the effective heating or radiating surface of the drum, and means located at the feed end of the drum for feeding the material to the said passages substantially as described.

2. A drier-drum having a solid partition fitted therein to form the drum into a plurality of passages through which the stock may be passed, and spirally-disposed flanges mounted at the feed end of the drum to advance the stock to the passages in the drum.

3. A drier-drum, having a solid continuous partition extending longitudinally through the same to form the drum into a plurality of independent passages, through which the material to be dried may be passed, flanges attached to said partition to advance the stock along the passages, and flanges arranged spirally at the feed end of the drum to advance the stock to said passages in the drum, substantially as described.

4. A drier-drum having solid partitions arranged radially with respect to the drum, angle-irons securing the partitions to the sides of the drum, and angle-irons securing the partitions to each other at the center of the drum, the feed end of the drum being provided with a series of angle-irons arranged spirally on the inner surface of the feed end of the drum and serving, as the drum revolves, to feed the material into the passages, the said partitions being provided with angle-iron

flanges to move the stock along the drum, substantially as described.

JOHN BISHOP.

ANDREW PETER JERGUSON.
